Attorney.

UNITED STATES PATENT OFFICE.

WILLIAM YOXALL, OF MANCHESTER, ENGLAND.

DEVICE FOR THE PRODUCTION OF CREASES IN TROUSERS.

Application filed May 8, 1923. Serial No. 637,558.

To all whom it may concern:

Be it known that I, WILLIAM YOXALL, a subject of the King of Great Britain and Ireland, and resident of Old Trafford, Manchester, in the county of Lancaster, England, have invented certain Improvements in Devices for the Production of Creases in Trousers, of which the following is a specification.

10 This invention relates to improvements in means for producing and retaining creases in trousers, the object being to provide a simple device for the purpose and means attached to the inside of each trouser leg for 15 retaining the crease in proper shape after the operation of forming it has been completed.

My invention consists essentially of a 20 board of suitable length provided with a longitudinal groove, a cord attached to one end of the board and adapted to be stretched over the cloth of the trouser so as to press the cloth into the groove, means for holding the other end of the cord and a narrow strip 25 of thin cloth or the like adapted to be attached to the cloth of the trouser and to remain thereon permanently.

My invention will be fully described with 30 reference to the accompanying drawing in which,

Fig. 1 is a plan of the device for forming the crease in the trouser leg,

Fig. 2, longitudinal section of same,

Fig. 3, end elevation of same, and

35 Fig. 4, partial transverse section of the board to an enlarged scale.

In carrying out my invention I provide a support which may be a wooden board *a* of suitable length and width and form in it 40 longitudinally a groove *b* of suitable size in accordance with the character or size of the crease it is desired to produce. In connection with the groove *b* I employ a cord *c* adapted to be fixed at one end *d* to the board 45 whilst the other end of the cord is arranged to be secured to the other end of the board by suitable holding means after it has been stretched. Such holding means may consist of any ordinary bradawl or a convenient 50 form of clamp such as an ordinary clamp *e* provided with a screw *f* in either case to securely hold the cord in the stretched con-

dition. Prior to stretching the cord in the manner described the trouser leg *g* is turned inside out and arranged on the board in a straight condition and in the proper position for having a crease made in it. The cord is then stretched tightly over the cloth of the trouser and pressed into the latter by means of a heating iron of any suitable type 55 so as to cause the cloth to assume the section shown in Fig. 4. By using a cord of flexible material, and securing it over the cloth under tension, a perfectly straight crease can be made in the trousers. The straight 60 cord obviates the necessity of making a preliminary crease in the cloth, and the cord holds the cloth in position on the ironing board while the cloth is being ironed. I 65 then take a narrow strip of thin textile or 70 other suitable material *g*¹ which may have straight edges *h* or serrated edges as shown at *i* Fig. 1, such strip being provided with any suitable adhesive which will adhere to 75 cloth. The adhesive may be applied to the strip at each side of the cord leaving a portion in the centre entirely free from adhesive. By the use of a heated iron the strip is pressed so as to adhere to the cloth whilst 80 the latter is in the flat condition and after the operation of pressing is completed the 85 cord clamping means is removed and the cord drawn from under the strip, the latter retaining the crease in the trouser. The strip is sufficiently thin as not to show on the outside of the trouser leg when the latter 90 is stretched and yet is sufficiently strong to retain the crease formed in the cloth.

What I claim as my invention and desire to secure by Letters Patent is:—

In an apparatus for creasing trousers, an ironing board having a straight longitudinal groove in its top surface, a cord adapted to be arranged in the groove over the material to be creased and secured to the board at one 95 end of the groove, and a screw clamp secured to the board at the other end of the groove and adapted to hold the cord in the groove under tension, said cord operating to retain a portion of the cloth in the groove and permit the cloth to be ironed on the board.

In testimony whereof I hereunto set my hand,

WILLIAM YOXALL,
